ROTARY ENGINE.

1,259,857.

Specification of Letters Patent. Patented Mar. 19, 1918.

Application filed July 17, 1915, Serial No. 40,458. Renewed September 26, 1917. Serial No. 193,388.

To all whom it may concern:

Be it known that I, MANDIUS B. HAGA, a citizen of the United States, residing at Garberville, in the county of Humboldt and State of California, have invented certain new and useful Improvements in Rotary Engines, of which the following is a specification, reference being had to the accompanying drawings.

10 This invention relates to rotary engines, and particularly to rotary engines of that type wherein the rotor is provided with blades which are movable radially with relation to the rotor and in which the rotor casting is provided with an abutment, the blades being depressed into the rotor to pass said abutment by means of suitable mechanism acting automatically to this end, and again forced out after the blades have passed the 20 abutment.

The primary object of the invention is the provision of a rotary engine of this type, so constructed that the rotor may be driven in either direction.

25 A further object is to improve upon the details of construction and to simplify the mechanism of such rotary engines, and still another object is to provide a fixed ring disposed in the middle plane of the rotor, 30 through which ring the inlet ports and exhaust ports pass, and so construct the rotor that flanges bear against the side faces of this ring thus permitting the rotor and ring to be packed evenly, reducing the friction 35 of the rotor and the ring and very much increasing the effectiveness of the engine.

Other objects will appear in the course of the following description.

40 My improved rotary engine is illustrated in the accompanying drawings, wherein:

Figure 1 is a side elevation of the rotary engine with one of the side plates and the corresponding flange removed, a portion of the rotor casing being shown as broken away;

Fig. 2 is an end view of the engine;

Fig. 3 is a vertical diagrammatic section of the engine;

Fig. 4 is a top plan view of the member 17;

Fig. 5 is a side elevation of the member 17;

Fig. 6 is a section on the line 6—6 of Fig. 1.

55 Referring to these drawings it will be

seen that the casing proper of the engine consists of the oppositely disposed plates 2, these plates being fixed and both of the plates being alike. Each of these plates is preferably formed with an eccentric track or groove 3 whose purpose will be later described. A shaft 4 passes through the plates and forms the driving shaft upon which the rotor is mounted, and the rotor 5 mounted thereon consists of a medially disposed hub portion 6 having oppositely disposed circumferentially extending flanges 7. These flanges 7 at their edges are inwardly bent or extended to form flanges 8, the inner faces of these flanges being spaced from each other as illustrated clearly in Fig. 3. The hub portion 6 is formed at diametrically opposite points with the inwardly extending recesses 9 within which the piston blades 10 are mounted. The plates 7 of the rotor are slotted, as at 11, in alinement with each of these pockets or recesses 9, and each of the blades 10 is provided with oppositely projecting pins 12 which pass through these slots 11 and carry at their ends the somewhat elongated heads 13. These heads are made to conform to the grooves or tracks 3 so as to travel easily around said grooves and be guided thereby.

The grooves 3 are so formed as to cause the projection of these piston blades 10 during a portion of the rotation of the rotor, and a retraction of these blades upon the remainder of the rotation. As illustrated in Fig. 1, each groove 3 is circular for a portion of its length, as from *a* to *b*, this portion *a*, *b*, corresponding to the lower portion of the travel of the piston blade, and being concentric to the shaft 4. The upper portion of the track, from *b* to *a*, is eccentric to the shaft 4 and presents a relatively flattened curve which will act to draw the piston blade gradually inward until at the top of the curve or highest point of travel of the piston blade the piston blade will be entirely drawn into the recess 9.

Rigidly connected to the side walls 2 of the casing and disposed between the inwardly turned flanges 8 of the rotor is an annulus 14 having any desired thickness. 105 The faces of the flanges 8 contact with these annulus and a packing is interposed between these flanges and the annulus as will be later described. The exterior edge of the annulus 14 is circular and the interior face 110

of the annulus for the greater portion of its length is circular, but at one point in its diameter the interior or inner face of the annulus is thickened so as to provide an abutment 15, the inner face of this abutment gradually merging into the curvature of the inner face of the remainder of the annulus, as shown clearly in Fig. 1. This thickened portion 15 of the annulus is cut away as at 16 to form a recess to receive within it a packing member 17 which is yieldably urged toward the periphery of the rotor. This packing member has a length equal to the distance between the members 7 and 15 normally bears yieldingly against the periphery of the rotor. The member 17 is braced at its ends by means of bracing members 17^a. On each side of the recess 16 are formed inlet ports 18 which are connected as by a pipe 19 to a casing of a rotatable valve 20 so formed that the fluid used to operate the rotor may be directed into one of the ports or into the other of the ports as desired. The annulus 14 is also formed with outlet or exhaust ports 21 disposed diametrically opposite each other and nearly in line with the shaft 4. These ports 21 are connected as by means of a pipe 22 to a valve casing 23 and in which is mounted a valve 24 adapted to connect one or the other of the ports 21 with the open air or to a muffler (not shown).

The inwardly turned flanges 8 of the rotor are formed upon their inner edges with packing recesses 25, within which are mounted packing rings 26 which bear against the side faces of the annulus 14. These packing rings have steam tight engagement with the side faces of the annulus 14. At diametrically opposite points the annulus 14 is outwardly extended, as at 27, to form lugs, these lugs serving as means whereby the annulus may be rigidly connected to the casing plates 2 as by means of transverse members 28, these members being illustrated as in the form of plates. Of course there may be as many of these lugs 27 as desired, though I have illustrated only two. Preferably the flange plates 7 are bolted to the hub portion of the rotor so that they may be readily removed, replaced, or tightened up. By tightening up the bolts by which these plates are held to the rotor, it is possible to cause the flanges 8 to contact more tightly with the face of the rotor and thus increase the effectiveness of the packing rings.

The operation of my invention will be obvious from the above description. Assuming that steam or other fluid pressure is being admitted into the rotor chamber on the left hand side of the abutment 15, and that the port 21 on the right hand side of the rotor chamber is open and the opposite exhaust port is closed and the inlet port

opposite to the open inlet port is also closed, then it will be obvious that the fluid pressure admitted through the left hand port 18 will cause the rotor to move in a counter-clockwise direction and that the fluid pressure will continue to act until the piston blade has passed the exhaust port 21 on the right hand side. Then as the blade nears the abutment 15 it will be gradually forced inward by the eccentricity of the tracks or grooves 3 until when it passes the member 17 the blade will be fully withdrawn and pass beneath said member. Then the blade will be gradually pushed outward again into contact with the inner face of the annulus 14 and the inwardly extending flanges 8, and the steam pressure behind it will continue to urge the rotor in a circular path.

While I have illustrated the side plates 2 as formed with tracks 3 for the purpose of withdrawing or projecting the blades 10, I do not wish to limit myself to this as other means for projecting the blades may be used. In many ways the details of construction may be varied within the scope of the claims without departing from the spirit of the invention and therefore I do not wish to be limited to these details. It will be noted that I have provided a rotary engine wherein only a small portion of the rotor frictionally engages the rotor casing. Thus if other means are provided for retracting and projecting the blades it will not be necessary to use the side plates of the rotor casing but the annulus will alone be used and thus the rotor would have only a minimum engagement with a non-rotating part.

Having thus described my invention, what I claim is:

1. In a rotary engine, a rotor, radially movable blades mounted thereon, casing plates disposed on each side of the rotor, a fixed annulus surrounding the rotor and having a thickness less than that of the rotor and being rigidly connected to the side plates of the casing, the rotor having flanges at its side edges overlapping the annulus, the margins of the flanges being inwardly turned to engage against the opposite faces of the annulus and having fluid-tight engagement therewith, said annulus having an abutment at one portion of its circumference, and extending across the space between the flanges of the rotor, the annulus having an inlet port on one side of the abutment and an outlet port on the opposite side of the abutment, and means for retracting the blades as they approach the abutment and projecting the blades after they have passed the abutment.

2. In a rotary engine, a rotor formed on its periphery with a plurality of recesses, blades mounted in said recesses for radial movement, the rotor having flanges extending outward on each side of the blades and

beyond the blades, said flanges at their edges being inwardly turned, casing plates disposed on each side of the rotor and extending out beyond the periphery thereof, an annulus rigidly connected to said casing plates and disposed between the inwardly extending portions of the rotor flanges and with the inner face of which said blades engage, said annulus being formed at one portion 10 of its inner surface with an inwardly extending abutment, the abutment being radially recessed, said annulus being less in width than the width of the rotor and blades, a member disposed in the recess of the annulus and extending transversely thereacross and having a width equal to that of the blades, outlet and inlet ports formed in the annulus at opposite sides of the abutment, and means for causing the retraction 15 of the blades as they near the abutment and the projection of the blades after they pass the abutment.

3. In a rotary engine, a rotor having radially disposed recesses on its face, radially 25 movable blades mounted in said recesses, blades disposed on each side of the rotor and forming part thereof and extending beyond the periphery of the rotor and having inwardly extending margins, the faces 30 of the margins being grooved, packing rings disposed in said grooves, an annulus having a thickness less than that of the rotor disposed between the inwardly turned flanges 35 of the rotor, the inner face of the annulus being formed at one point with an abutment projecting toward the periphery of the rotor, this abutment being recessed, the annulus also being formed with oppositely disposed exhaust ports on each side of the abutment, oppositely disposed casing plates dis- 40

posed on each side of the rotor and to which the annulus is rigidly connected, means for retracting the blades into the recesses of the rotor as they approach the abutment and projecting said blades after they pass said 45 abutment, and means for directing motive fluid into either one of said inlet ports and means for opening either one of the exhaust ports.

4. A rotary engine comprising a rotor hub 50 recessed at a plurality of points upon its periphery, radially movable blades disposed in said recesses, an annulus surrounding the rotor and less in thickness than the rotor, said annulus at one point in its periphery 55 being formed with an abutment, the abutment being radially recessed, a member disposed in the recess of the abutment and having a length equal to the thickness of the rotor and the length of the blades, the plates 60 mounted upon the rotor hub on each side thereof extending outward beyond the periphery thereof having inwardly extending flanges bearing against and having fluid tight engagement with opposite faces of the 65 annulus, and means for causing the retraction of the blades as they approach the abutment formed on the annulus and the projection of the blades as they pass said abutment, said annulus being provided with an 70 inlet port on one side of said abutment and an outlet port on the opposite side of said abutment.

In testimony whereof I hereunto affix my 75 signature in the presence of two witnesses.

MANDIUS B. HAGA.
